UNITED STATES PATENT OFFICE.

CHARLES W. WIPFLER, OF DETROIT, ASSIGNOR TO FRANK P. GLAZIER, OF CHELSEA, MICHIGAN.

DESIGN FOR AN OIL-STOVE.

SPECIFICATION forming part of Design No. 23,972, dated January 29, 1895.

Application filed November 19, 1894. Serial No. 529,324. Term of patent 7 years.

To all whom it may concern:

Be it known that I, CHARLES W. WIPFLER, a citizen of the United States, residing at Detroit, in the county of Wayne and State of Michigan, have invented and produced a new and original Design for Oil-Stoves, of which the following is a specification, reference being had therein to the accompanying drawing, which shows the same in perspective.

The base of the stove is formed by the oil tank casing A, presenting a plain cylindrical face, having beaded bands B.

C is an ornamented bottom ring, having its lower edge B shaped to conform to the lower edge of the surface scroll ornamentation E, which scroll ornamentation extends in both directions from a central point between the legs F. The legs have the foot section a which enlarges and merges into the substantially semi-globular head G extending over the bottom ring, terminating in a semi-circular standard H, which extends to the top of the tank A. The face of the leg is ornamented by grass like blades on the foot section, terminating in an oval shaped field over the head G in which are pointed leaf shaped ornamentations I. The standard H is ornamented in the same manner as the foot. Above the tank A is the ring J which in contour has a graceful inward curve from its lower edge to the upper edge. This ring has a Moorish surface ornamentation of the following description:

K is a pointed leaf like ornament having the short scrolls L extending from the base, 35 and involute scrolls M extending there-

through along the lower face of the ring, the ends of the adjoining scrolls M being connected by an ovate shaped loop or leaf N. The upper portion of the ring being, thus, ornamented only by the alternate pointed and 40 ovate ornamentations N and K, the whole has the appearance of a foliated ornamentation.

Above the ring J is the combustion chamber casing O gracefully curving outwardly 45 from the top of the ring J to its middle and inwardly from its middle to its cap ring P. The doors form central panels on this casing, and above each door are the scroll ornamentations P'. Above this ring P is the cylindrical 50 top, Q, on which is a cap having a plain molded lower edge R, and an open scroll ornamented top, terminating in an urn shaped cap ornament S.

The leading features are, first, the peculiar 55 design for the base section as shown, and, second, the general design of the stove as a whole as shown.

What I claim as my invention is—

1. In a design for a stove, the base substantially as herein described and shown.
2. The design for a stove herein described and shown.

In testimony whereof I affix my signature in presence of two witnesses.

CHARLES W. WIPFLER.
